UNITED STATES PATENT OFFICE.

WALTER F. ROGERS, OF CHICAGO, ILLINOIS.

STOVE.

1,355,848.

Specification of Letters Patent. Patented Oct. 19, 1920.

Application filed August 23, 1919. Serial No. 319,446.

To all whom it may concern:

Be it known that I, WALTER F. ROGERS, a citizen of the United States of America, and a resident of Chicago, county of Cook, 5 and State of Illinois, have invented certain new and useful Improvements in Stoves, of which the following is a specification.

This invention relates to that class of stoves in which the oven is heated by the 10 combustion of either solid or gaseous fuel. In stoves of this type, a gas burner is generally mounted inside of the oven, and a fire-box for the combustion of solid fuel communicates with a heat passage located in 15 the walls of and beneath the oven.

The main objects of the present invention are to provide an improved form of hollow partition in the heat passage beneath the oven adapted to serve as a baffle wall for 20 uniformly distributing the heat from the combustion of the solid fuel, and also as a conduit for delivering the secondary supply of air to the gas burner within the oven; and to provide an improved form and arrangement of valve means for controlling the flow of air through said hollow partition. 25

An illustrative embodiment of this invention is shown in the accompanying drawings, in which—

Figure 1 is a horizontal sectional view of the oven showing a ring shaped gas burner mounted therein.

Fig. 2 is a longitudinal sectional view of the same, taken on the line 2—2 of Fig. 1.

Fig. 3 is a perspective view of the improved form of hollow partition.

Fig. 4 is a perspective view of the improved valve means for controlling the admission of air to the partition.

In the common form of kitchen range which is adapted for the combustion of solid fuel, the fire-box is generally located at one side of the oven, and the hot gases from the fire-box pass over the top of the oven down around the opposite side thereof and then back through the heat passage which is located beneath the oven. In this type of stove, a baffle wall or flue strip in the 45 form of a partition is secured in the heat passage beneath the oven, so as to uniformly distribute the heat beneath the bottom of the oven by causing the hot gases to travel in a circuitous path before they reach the smoke flue. Heretofore this partition, which forms the baffle wall, has generally

been in the form of a vertically disposed sheet of metal extending diagonally from one corner of the heat passage to substantially the center thereof.

In stoves constructed to embody the invention disclosed in my copending application, Serial No. 205,072, filed December 3, 1917, in which a gas burner is mounted within the oven, an opening is formed in 60 the base plate of the oven to serve as a secondary air inlet for the gas burner. In the latter construction, it is also necessary to provide a baffle wall in the heat passage beneath the oven to distribute the heat when the stove is burning a solid fuel.

In the present invention, the baffle wall in the heat chamber and the secondary air inlet for the gas burner are combined in a single device in the form of a hollow partition open at the back of the stove, and the opening in the bottom of the stove is avoided. In the construction shown in the drawings, the invention is embodied in a kitchen range comprising an oven 1 having 70 a gas burner 2 mounted therein, and a fire-box 3 located at one side of the oven for the combustion of a solid fuel.

The top of the oven is spaced from the top plate of the stove, so as to form a heat passage 4 communicating at one end with the fire-box 3 and at the other end with a passage 5 formed at the side 6 of the stove. The bottom of the oven is formed of double walls so as to provide a heat passage 7 which communicates with the fire-box through the passages 4 and 5. When the stove is burning solid fuel, the heat travels through the passages 4, 5 and 7 in the direction of the arrows shown in Fig. 2.

The gas burner is similar to that shown in my copending application, above mentioned, and comprises a ring-shaped burner seated in depressions which are formed in the inner base plate 8 of the oven, said base plate having an opening 9 within the area circumscribed by the ring burner. The lateral arm of the burner is also seated in a depression formed in the inner base plate 8 and extends diagonally outward and passes through an opening formed in the rear wall of the oven where it communicates with a fuel inlet and a primary air inlet.

The improved partition may be cast in one hollow piece if desired, but the preferable construction is that shown in the drawings, in which the partition comprises a

- pair of separate members 10 cast to the form shown in Fig. 3 and secured together by a bolt 11. In its assembled form, the partition is of U-shape and comprises a cylindrical part 12 having a pair of parallel legs 13 extending to one side therefrom and spaced apart as shown. The partition is mounted in the heat passage 7 so that the cylindrical part 12 is located in alignment 5 with the opening 9 of the base plate 8. The legs 13 are disposed directly beneath the lateral arm of the gas burner, the upper edges of said legs being curved to conform to the depression in the base plate 8, which 10 forms the seat for the lateral arm of the burner. The outer end of the partition communicates with an opening in the rear wall of the oven, which forms a secondary 15 air inlet for the gas burner.
- 20 The valve for controlling the flow of air through the inlet, preferably comprises a strip of metal 14 cast to the form shown in Fig. 4. The valve 14 is slidably mounted in guideways formed in the rear wall of the 25 oven and is adapted to be shifted into and out of position to close the air inlet.

The means for shifting the valve 14 comprises a rod 15 rotatably mounted in bearings secured to the side 6 of the stove. The 30 rear end of the rod 15 is formed to provide a crank 16 which engages a slot 17 formed at the outer end of the valve 14 so that the rotation of the rod will shift the valve in its guideways. A handle 18 is formed at 35 the forward end of the rod 15 to facilitate the rotation thereof.

In the operation of the device, when the 40 stove is burning a solid fuel, the valve 14 is shifted to its closed position and the heat from the fire-box passes through the heat chamber 7 to a smoke flue 19 in the usual way. In heating the oven by the gas burner,

the valve 14 is shifted to its open position so that a secondary supply of air passes through the hollow partition to the gas 45 burner.

Although but one specific embodiment of this invention has been herein shown and described, it will be understood that numerous details of the construction shown may be 50 altered or omitted without departing from the spirit of this invention as defined by the following claim.

I claim:

In a stove adapted for burning either solid 55 or gaseous fuel, a fire-box for the combustion of solid fuel, in combination with an oven having a ring-shaped gas burner mounted therein, a lateral arm extending radially outward from said burner and communicating at its outer end with fuel and air inlets, the bottom of said oven comprising inner 60 and outer plates disposed in substantially parallel spaced relation to form a heat passage communicating with said fire-box, said inner plate having a depression therein to form a seat for said ring burner and lateral arm, a hollow baffle wall disposed in said heat passage for uniformly distributing the 65 heat beneath said oven, one end of said hollow baffle wall communicating with said oven through an opening in said inner plate, the other end communicating with said air inlet, whereby said baffle wall is adapted to 70 serve as a secondary air conduit for said 75 gas burner, said baffle wall extending in the same direction as said lateral arm and having its upper face shaped to conform to the depression in which said burner arm is seated.

Signed at Chicago this 12th day of August, 1919.

WALTER F. ROGERS.
